(57) **CLAIM**

The ornamental design for a sealant removal reversible
socket for hex head fasteners as shown and described.

DESCRIPTION

FIG. 1 is a perspective view of a sealant removal reversible
socket for hex head fasteners;

FIG. 2 is a front elevational view thereof;

FIG. 3 is a top plan view thereof;

FIG. 4 is a bottom view thereof;

FIG. 5 is a perspective view of a sealant removal reversible
socket for hex head fasteners in an alternate state of use;

FIG. 6 is a front elevational view of FIG. 5, the rear view
being a mirror image thereof; and,

FIG. 7 is a top plan view of FIG. 5.

The broken lines in the figures depict environmental structure
that forms no part of the claimed design.

1 Claim, 6 Drawing Sheets
